EXHAUST STEAM INJECTOR

Emanuel Rawson, North Bergen, N. J., assignor
to The Superheater Company, New York, N. Y.

Application March 7, 1934, Serial No. 714,384

19 Claims. (Cl. 103—265)

The present invention relates to exhaust steam injectors and has particular reference to exhaust steam injectors of the type adapted to be applied as boiler feeding devices for locomotive boilers. 5 Still more particularly the invention relates to exhaust steam injectors of the above character and control systems therefor adapted to be actuated by the pressure of live steam admitted to the locomotive engine for automatically causing the injector to be operated wholly by live steam when exhaust steam from the locomotive engine is not available and for causing the injector to be operated by exhaust steam from the locomotive engine when such steam is available. 10 Control systems actuated by the pressure of live steam admitted to a locomotive engine for causing such automatic change in operation of exhaust steam injectors are known broadly and have been utilized commercially with varying degrees of success. Practical experience with such injectors and control systems has demonstrated that certain undesirable characteristics of operation occur in practical service which would not be expected from a theoretical consideration of the 15 functioning of the apparatus, and it is one of the principal objects of the present invention to improve upon the construction of a live steam actuated control or change-over system so as to eliminate the faults in operation which practical experience has shown to exist in previous systems 20 of the character under discussion.

One of the principal functions of exhaust steam injectors, as applied to locomotives, is to conserve fuel by returning to the boiler as much 25 as possible of the exhaust steam from the engine, which heat is recovered by condensation of the exhaust steam in the injector. Experience has proved that under practical operating conditions, certain combinations of operating factors may arise which render operation of an injector by exhaust steam undesirable, if not impossible, and control systems heretofore developed have provided means whereby under the 30 control of the operator the injector may be positively shifted to live steam operation in spite of the presence of high pressure steam in the engine supply line which would normally act to shift the injector to exhaust steam operation. Experience has shown that with a control system 35 provided with a so-called emergency position which insures operation of the injector as a live steam injector, regardless of the presence or absence of exhaust steam, the tendency of the operators of the injectors is, if the injector is once 40 shifted to the emergency position, to forget to

return the control system to a normal operating position and to allow it to continue to operate in the emergency. It is evident that with the control system in the emergency position and with the injector operating wholly on live steam, its utility as a heat and fuel conserving agency is lost, and another of the principal objects of the present invention is to provide an improved control apparatus which will permit of emergency operation on live steam but in which this emergency operation is accompanied by a condition which will serve as a constant reminder to the operator that the injector is not functioning in its normally intended manner to make use of exhaust steam when such steam is available. 5

Other and more detailed objects of the invention and the manner in which the above general and detailed objects thereof are attained may best be understood by the ensuing description of suitable forms of apparatus for carrying the 10 invention into effect, taken in conjunction with the accompanying drawings forming a part of this specification, in which

Fig. 1 is a more or less diagrammatic elevation of part of a locomotive showing injector apparatus embodying the present invention; 25

Fig. 2 is a more or less diagrammatic section on a larger scale showing part of the injector and the valve apparatus illustrated in Fig. 1;

Fig. 3 is a view similar to Fig. 2 showing a 30 different form of apparatus; and

Fig. 4 is a view on a still larger scale of part of the apparatus shown in Fig. 3.

In Fig. 1 the boiler of the locomotive is indicated generally at 10 and the operator's cab at 12. The injector indicated generally at A is mounted below the cab and is supplied with water from the engine tender (not shown) through pipe 14. Overflow from the injector during priming periods passes through the overflow pipe 16 and water is delivered by the injector to the boiler through the delivery pipe 18. Exhaust steam for operating the injector is conducted from a suitable place in the exhaust passage of the engine cylinder 20 through the exhaust steam supply pipe 22, and live steam for actuating certain parts of the control system and for operating the injector is supplied from the boiler turret 24 through the pipe 26 in which is located the main control valve B, the latter being connected with the injector by means of the steam supply pipes 28 and 30. Valve B is provided with an manual control in the form of a hand wheel 32 located in the cab 12. Also located in cab 12 is the water control handle 55

34 for governing the amount of water supplied to the injector. Mounted adjacent to the main control valve B is the automatic or change-over valve C, the function of which will be explained later. This valve is connected with the injector body by means of pipe 36. The change-over valve C is connected by means of pipe 38 to a relay valve D which is in turn connected to the steam chest of the engine cylinder 28 or to the steam supply line leading to the steam chest by means of pipe 40. Live steam from the pipe 28 is supplied to the relay valve through pipe 42 and a vent pipe 44 connects the body of the relay valve with the body of the injector. Pipe 46 leads from the relay valve body to the interior of the cab 12 and is provided with a manually controlled valve 48. The discharge from valve 48 is open to the atmosphere at 50 and fluid discharged at 50, when valve 48 is open, is caught in a suitable pan or funnel 52 from which it is conducted through the drain pipe 54 to the ash pan of the locomotive or other suitable place. Relay valve D is also vented to atmosphere or other suitable zone of low pressure by pipe 56.

25 Turning now to Fig. 2, in which the parts are shown in section, the injector illustrated is of known type and comprises a housing providing a main low pressure steam chamber 58 to which exhaust steam is admitted from pipe 22 under the control of the exhaust valve 60. Valve 60 is closed by spring 62 and is opened by live steam pressure acting on piston 64. Steam is admitted to piston 64 from pipe 36 leading from the change-over valve C.

30 Steam from chamber 58 flows to the main low pressure steam nozzle and water is admitted from the chamber 68 which is in communication with the supply pipe 14. The amount of water fed to the injector is controlled by moving nozzle 66 longitudinally of the injector body by means of the control apparatus comprising the rotatably mounted spindle 70 having an eccentrically mounted pin 72 engaging a suitable recess in nozzle 66. Spindle 70 is connected by means of 35 the control rod 74 with the operating handle 34 located in the cab of the locomotive.

35 The main control valve B in the form illustrated comprises two valve parts. The first part 40 76 constitutes a valve head seating to shut off all flow of live steam from pipe 26 to the injector and control system. Valve head 76 is connected so as to move longitudinally with the threaded control spindle 78 which carries the hand wheel 50 32. A second valve head 80 is connected to the valve head 76 by means of a suitable lost motion connection 82. Valve head 76 controls flow of steam from pipe 26 to chamber 84, the latter being connected by means of pipe 28 and passage 86 in the injector to the high pressure steam nozzle 88. Nozzle 88 will hereinafter be referred to as the supplementary steam nozzle and the steam supplied therethrough will be referred to as supplementary steam.

45 Valve head 88 controls flow of steam which has passed valve head 76 to the chamber 90, and this valve head is provided with a plug-like extension 92 forming a restriction or throttling orifice at the inlet of chamber 90. The automatic or change-over valve C comprises a valve member 94 having a double faced valve head 96 seating alternatively against upper and lower valve seats formed in chamber 90, which chamber is in communication with chamber 90. Valve member 94 has a piston 100 loosely fitted in the cylindrical chamber 102 and above this piston there is lo-

cated the check valve 104 seating to close communication between chamber 102 and a chamber 106 with which pipe 38 communicates. Below chamber 98 there is provided the chamber 108, placed in communication with chamber 98 by means of passage 110. Chamber 108 is in communication with the inlet of pipe 30. Pipe 30 is in communication by way of the passage 112 and ports 114 with the main steam chamber 58 of the injector.

10 The change-over valve member 94 is preferably provided with a suitable lower guide piston 116.

15 The apparatus which has been described above in detail constitutes one form of a live steam pressure actuated control system of a type which is known and which in prior installations has been actuated by admitting steam directly from the engine steam chests to the chamber 106 through a pipe such as 38 shown in Fig. 2. In 20 order to better understand the present invention, the operation of this portion of the apparatus, which constitutes prior art structure, and the nature of the faults in the operation thereof will now be explained.

25 Let it be assumed that the locomotive engine is running and exhaust steam for operation of the injector is available. Let it also be assumed that the main control valve B is open as shown in Fig. 2. With the valve head 76 open, supplementary steam at high pressure will be admitted to nozzle 88 and through a suitable known type of connection (not shown) a water valve controlling the flow of water to chamber 68 of the injector will be opened. The high pressure supplementary 30 steam and the water will serve to prime the injector.

35 Valve head 88, being open, permits live steam to flow to chamber 98, and valve head 96 being in the lower position shown in Fig. 2, live steam flows to chamber 102 and through pipe 36 to the exhaust valve piston 64, thus opening the exhaust valve and permitting exhaust steam to flow to chamber 58 and the main low pressure steam nozzle 66. With the valve head 96 in its lower position, flow 40 of live steam to chamber 108 and consequently through pipe 30 to the steam chamber 58 is prevented.

45 Under the conditions assumed, live steam from the engine steam chests is admitted through pipe 38 to chamber 106 and seats the check valve 104. Due to the fact that piston 100 is a loose fit in chamber 102, steam leaks past this piston to balance it and with this piston balanced the unbalanced pressure of steam in chamber 98, acting 50 on the valve head 96, serves to maintain the change-over valve member 94 in its lower position.

55 With the parts in the position described the injector functions as an exhaust steam injector utilizing exhaust steam from the engine and a small amount of high pressure supplementary live steam, the latter being supplied at all times when the injector is in operation. If we now assume that the engine throttle is closed so that exhaust steam is no longer available, the action is as follows:

60 Steam pressure in pipe 38 fails and the steam in chamber 106 and in the space between the check valve and piston 100 is vented to the engine steam 65 chests through pipe 38. Release of pressure above piston 100 causes this piston to become unbalanced and to lift the change-over valve member 94 so that valve head 96 seats against its upper seat to close communication between chambers 70 75

98 and 102 and open communication, by way of passage 110, for flow of steam from chamber 98 to the supply pipe 30 and to the main steam chamber 58 of the injector. At the same time, due to the loose fit of piston 100, steam from the pipe 36 escapes to pipe 38, thus permitting the exhaust valve 60 to close under the influence of spring 62.

When valve head 96 is on its lower seat, there is no flow of steam from chamber 102 (except for the leakage flow past the clearance space around piston 100 to the steam chests of the engine, which always have a somewhat lower pressure than boiler pressure when the engine is running) and consequently the pressure in this chamber is substantially equal to boiler pressure, but when the change-over valve shifts so as to open communication to the chamber 108 for flow of steam to the injector, the pressure of the steam admitted to chamber 98 is reduced by the throttling action of the restriction 92, so that the live steam admitted through pipe 30 to the injector is admitted thereto at a pressure approximating average exhaust steam pressure. This live steam of reduced pressure will hereinafter be referred to as "auxiliary steam".

When the valve head 96 is seated in its upper position, it will thus be evident that the lower face of this valve is exposed to the pressure of steam of only relatively low pressure. Consequently, when the engine throttle is again opened and high pressure steam from the steam chests is admitted to chamber 106, the pressure exerted on the upper face of piston 100 is ample to cause shifting of the valve back to its lower position. Check valve 104 does not interfere with the admission of steam to piston 100 since when the valve member 94 is in its upper position, the check valve 104 is mechanically lifted from its seat. For purposes of considering operation of the system, check valve 104 may be disregarded. This valve is provided only for the purpose of preventing leakage of live steam past piston 100 and into the injector during periods when the engine is running and the injector is not in operation.

In order to have satisfactory practical operation of the injector, it is highly desirable that the injector control system effect change-over of operation of the injector from live steam to exhaust steam and vice versa when the most favorable conditions obtain for such change-over. It is also highly desirable that the change-over be consistent. From a consideration of the mode of operation described above, it will be evident that the controlling factor in the change-over of operation is the difference in pressure between the two sides of the piston 100 of the change-over valve. By way of example, let us assume that the injector is operating on exhaust steam and that it is desired to have the injector shift over to live steam operation when the engine throttle is closed to an extent such that the pressure of the exhaust steam from the engine falls to a value of one pound or less above atmospheric. This condition of exhaust steam pressure will be represented by a corresponding relatively low steam chest pressure and consequently a relatively low pressure in pipe 38. Let it be assumed that the pressure in pipe 38 for this condition is 100 pounds per square inch and that the pressure of live steam from the boiler in chamber 102 is 200 pounds per square inch. As the pressure in pipe 38 drops from its normal pressure to a value considerably below that in chamber 102, flow of high pressure steam from chamber 102 to pipe 38 commences and the pressure in chamber 106 and con-

sequently pressure on the upper face of the piston is thus determined not alone by the steam chest pressure but also by the rate at which steam leaks into this chamber from chamber 102.

Experience has shown that due to unavoidable wear and other practical operating factors the amount of steam flowing past piston 100 cannot be kept constant over long periods of operation and consequently for a given steam chest pressure at the outlet of pipe 38 there may be variations of considerable magnitude in the pressure in chamber 106, which variations obviously effect the change-over of the system from one type of operation to the other. Many attempts have been made heretofore to correct the difficulties encountered with the type of valve under discussion due to the variations in its action, but long experience has shown that to change the construction in the different ways heretofore proposed leads to other difficulties in operation more disadvantageous than the difficulties sought to be remedied. Systems of the general character under discussion are comparatively very sensitive in operation and the relatively great number of factors which must be properly correlated render it extremely difficult to alter the change-over valve arrangement without incurring other operating difficulties.

A further cause of trouble in the valve arrangement under discussion is the fact that in locomotive installations, the injector is usually located adjacent the cab and consequently the pipe 38 leading to the steam chests is relatively long, and also, because of practical considerations, is of relatively small diameter. It has been found in service that this pipe at times may become partially restricted due to foreign matter such as scale, rust or the like in the pipe, and frequently becomes partially restricted due to the pipe becoming dented. Since, in practical installations, this pipe is frequently placed beneath the outer insulating cover of the boiler, it is extremely difficult to reach and restrictions in it may not be known. Any restrictions in this pipe which are of sufficient magnitude to materially alter the pressure drop between the ends of the pipe have the same effect of varying the steam chest pressure at which the injector changes over as does the wear in the valve which orders the rate of flow past the piston 100. The present invention eliminates the difficulties heretofore encountered with apparatus of the character described and provides further advantages not obtainable with apparatus heretofore used, in a simple manner and in a way such that the invention is readily applicable to existing installations as well as being applicable to new equipment.

The use of the invention in apparatus of a form applicable for installation with existing apparatus is shown in the embodiment illustrated in Fig. 2. In this embodiment there is interposed between the pipe 40 leading from the engine steam chest and the pipe 38 connected to the chamber 106 of the change-over valve, the relay valve mechanism indicated generally at D. This mechanism comprises a relay valve member 118 having a double faced head 120 located in chamber 122 with which pipe 38 communicates. When the valve head 120 is seated against the lower valve seat cooperating therewith, communication is closed between pipe 38 and the vent 56 and communication is established between pipe 38 and chamber 124 which is connected by means of pipe 42 with the high pressure steam supply pipe 28. The relay valve member 118 is provided at its

upper end with a piston 126 slidably mounted in the valve housing and having a small leak passage 128 passing therethrough. Passage 128 provides constant communication between chamber 124 and a chamber 130 located above piston 126. Restricted communication between chambers 124 and 130 may be provided by other means such, for instance, as a small passage in the valve housing or a clearance space between piston 126 and the housing. Chamber 130 is connected with chamber 132 by means of a vent port 134 and chamber 132 is vented by means of pipe 44, preferably to the low pressure steam chamber of the injector. Vent port 134 is controlled by the vent valve 136 which is in the form of a plunger, the upper end of which is located in chamber 138. Pipe 40 connects chamber 138 with the engine's steam chest or supply pipe. Vent valve 136 is urged toward open position by the spring 140 and the tension of this spring is preferably made adjustable as indicated.

As previously explained, the operation of the injector on exhaust steam or auxiliary live steam is determined by the presence or absence of steam of predetermined pressure in chamber 106 of the change-over valve, and the relay valve arrangement just described operates to control the pressure in this chamber in the following manner:

Let it be assumed that the injector is in operation and that the engine of the locomotive is running. Whenever the main control valve B is open, that is, whenever the injector is operating, high pressure live steam is supplied through pipe 42 to chamber 124 and, if the valve head 120 is in the lower position shown in the figure, this high pressure live steam flows through chamber 122 and pipe 38 to the chamber 106, causing the change-over valve to assume the proper position for exhaust steam operation. The position taken by the relay valve member 118 is determined by the presence or absence of pressure in chamber 130 above piston 126. If pressure is built up in chamber 130 so as to balance the piston 126, the valve will assume the position shown in the figure and, if the pressure in chamber 130 is released, the pressure of steam in chamber 124, acting on the lower face of the piston, will lift the valve member 118 so as to seat the head 120 in its upper position. In this position of the valve head, the supply of high pressure steam from pipe 42 to chamber 106 is cut off and chamber 106 is simultaneously vented to atmosphere through the vent connection 56. When pressure is released from chamber 106, the change-over valve, as previously described, shifts to change operation of the injector to live steam operation.

Due to the presence of the leak passage 128 through piston 126, chamber 130 is in communication with a source of high pressure live steam at all times when the injector is in operation and the presence or absence of a pressure in chamber 130 is determined by the position of the vent valve 136 (assuming the valve 48 in the cab for controlling the pipe 46 to be closed). As will be evident upon the drawings, the vent valve 136 will be closed when pressure in chamber 138 of steam admitted thereto from the steam chest or supply pipe through pipe 40 is sufficient to overcome the spring 140 and the pressure exerted on the lower face of the valve when the valve is closed.

The above described relay valve arrangement operates to eliminate the difficulties heretofore encountered and the possibility of change over of

the injector at varying steam chest pressures, for the following reasons:

Piston 100 of the change-over valve is actuated by a supply of high pressure steam flowing substantially directly from the boiler and of relatively constant pressure. While the boiler pressure may vary, it nevertheless is practically at all times at relatively high pressure, and even under conditions when the boiler pressure is abnormally low so that the pressure in chamber 106 is considerably below normal, the condition of low boiler pressure also reduces the pressure of the steam acting on the valve member 94 in opposition to the pressure in chamber 106 so that variations in boiler pressure may for practical purposes be neglected. The previously employed long pipe connection from the change-over valve to the steam chests is eliminated and in place of this long connection there is substituted the short and relatively free connection for venting the chamber 106 which comprises the pipe 38 connecting the change-over and relay valve housings and the direct atmospheric vent from chamber 122 by way of pipe 56, which pipe may be very short and which, if desired, may be omitted entirely, since the amount of steam escaping therethrough before the automatic valve shifts to seat in its upper position is very small. Thus, with the present arrangement, chamber 106 may be said to be freely vented to atmosphere and any increase in the amount of steam passing piston 100, due to wear in this piston, does not affect the pressure in chamber 106 because of the free venting of this chamber to the atmosphere. In practical operation the action of the apparatus is such that the change-over valve shifts substantially simultaneously in response to shift of position in the relay valve head 120, regardless of variations in clearance in the change-over valve mechanism due to wear or other causes. Due to the fact that steam from chamber 130 of the relay valve is vented through pipe 42 and does not have to pass through the long pipe 40 leading to the engine cylinders, the amount of steam flow through pipe 40 necessary to close the vent valve 136 or to relieve the pressure in the small chamber 138 so as to permit this vent valve to open, is so small that restrictions in pipe 40 which may occur in service have little, if any, effect upon the steam chest pressure required to effect opening or closing of the vent valve with any given adjustment of spring 140. Thus, instead of an apparatus which in service may cause change over of operation of the injector at different steam chest pressures, which is highly undesirable, there is provided in accordance with the present invention an apparatus which will consistently effect change over of the injector at the steam chest pressure for which the apparatus is set. Furthermore, the apparatus provided by the present invention permits, through the adjustment of the tension on spring 140, an accurate control of the steam chest pressure at which the apparatus will function to effect change over of the injector operation. As a result of this, it is possible to readily set the change over system so that change over will take place at the most advantageous pressure for any given locomotive to which the injector apparatus may be applied. This feature of ready adjustability is not possible of attainment with prior systems.

Considering now the matter of the provision of an emergency position whereby the injector may be caused to operate as a live steam injector at the will of the operator, regardless of the pres-

ence or absence of exhaust steam, it will be evident that if the valve 48 in the cab is opened by the operator, chamber 130 of the relay valve will be vented to atmosphere through pipe 46 regardless of whether or not the vent valve 136 is opened or closed. If valve 48 is open, the action of the relay valve will be the same as if the vent valve 136 had been opened by failure of pressure in pipe 40, the change-over valve will consequently be shifted to auxiliary live steam operating position, and the change-over valve will remain in this position so long as valve 48 is open. However, when valve 48 is open, steam from chamber 124, leaking constantly through the passage 128 to chamber 130 and normally passing through pipe 44 when valve 136 is open, flows to atmosphere in the cab at 50. This constant supply of steam, although relatively small in quantity, provides a constant and annoying reminder to the operator that the injector is in emergency position and, as a result, the operator can be depended upon, as soon as the conditions requiring emergency operation have ceased to exist, to close valve 48 and thus restore the control system to normal operation in which exhaust steam will be utilized when it is available.

Turning now to Figs. 3 and 4, another form of apparatus embodying the invention is shown, in which the separate change-over valve and relay valve structures of Fig. 2 are dispensed with and a combined change-over and relay valve arrangement is substituted.

In Fig. 3 the form and arrangement of the injector A and the main control valve B are the same as that previously described, except that in the control valve the choke or throttling member 92 is dispensed with.

In the present arrangement chamber 90 of the main control valve is in communication with a chamber 150 which is connected with chambers 152 and 154 by passages 156 and 158, respectively. A double headed change-over valve 160 is arranged with a lower piston-like head 162 located in chamber 152 and an upper, double faced head 164 located in chamber 154. Chamber 152 communicates with the auxiliary steam supply pipe 30 in which is located an adjustable restricting valve 166 for reducing the pressure of auxiliary steam flowing to the injector. Chamber 154 communicates with chamber 168 by way of passage 170 and is also placed in communication with the exhaust valve operating piston 64 by pipe 36. Chamber 168 is vented to atmosphere or other zone of low pressure by pipe 56. Below the piston head 162 is chamber 172 which communicates by way of the vent port 174 with chamber 176. Pipe 46 leading to the emergency control valve 48 in the cab also communicates with chamber 172. Pipe 44 vents chamber 176, preferably to the low pressure steam chamber of the injector.

Vent port 174 is controlled by the vent valve 178 carried by diaphragm 180 and urged toward open position by spring 182, the tension of which is preferably made adjustable as indicated. Below the diaphragm 180 the casing structure provides a chamber 184 in communication with chamber 186 by way of ports 188. Chamber 186 is connected by pipe 40 to the steam supply line of the engine.

The details of construction of the form of valve head 162 are shown on an enlarged scale in Fig. 4. As shown in this figure, the lower valve head 162 is loosely mounted on the stem of the valve member 160 between collars 190 and 192 so

as to have a limited amount of longitudinal play with respect to the stem of member 160. The bore of head 162 also provides a clearance space 194 and the lower end of the bore is notched or recessed as shown at 196. Clearance space 194 and recess 196 provide for constant restricted communication between chambers 152 and 172, which restricted communication may be provided by other specific forms of passages.

The operation of this form of apparatus is as follows:

The presence or absence of steam from the supply line to the engine in chamber 184 determines the position of the vent valve 178 and consequently determines the presence or absence of pressure in chamber 172, to which chamber a restricted quantity of steam can flow by way of the clearance space 194 and recess 196. The presence or absence of pressure in chamber 172 determines the position of the change-over valve 160. When the engine is not operating and chamber 172 is vented through port 174, the pressure of steam in chamber 150 acting on the upper face of head 162 over-balances the pressure acting in the opposite direction on the smaller upper head 164 and the valve assumes the position shown in the drawings so as to admit auxiliary steam to the injector. In this position of the change-over valve, head 164 seats to close passage 158, thus cutting off the supply of actuating steam supplied to the exhaust valve from chamber 154 by way of pipe 36. At the same time chamber 154 is vented to atmosphere by way of passage 170 and pipe 56, thus releasing all pressure from pipe 36 so that the exhaust valve can close. With the change-over valve member in this position, high pressure live steam can, as previously pointed out, leak past the head 162 to the chamber 172 so that when the admission of steam to the engine supply line causes the vent valve 178 to be closed, pressure will build up in chamber 172 to over-balance the change-over valve and cause it to move to its upper position. In its upper position the upper valve head is shifted to close passage 170 and to open passage 158 so as to admit actuating steam to the exhaust valve piston 64 and cause the exhaust valve to be opened. At the same time the seating of the lower head 162 closes passage 156 connecting chambers 150 and 152 to shut off the supply of auxiliary live steam to the injector. In the upper position of the change-over valve member it will be evident that both the upper face of the upper head 164 and the upper face of the lower head 162 must seat and in order to insure proper seating of both of these heads, they are preferably not rigidly connected to each other.

It will be evident that the arrangement just described provides the same advantages over existing systems as the arrangement shown in Fig. 2. The construction does not involve the flow through the pipe 40 of any leakage steam and, consequently, the steam flow through this pipe at any time is so small that the resistance to flow through the pipe is a negligible factor. The change-over valve is positively actuated by live steam at high pressure and fluctuations in the pressure of this live steam are of no consequence since all of the pressures affecting the positioning of the valve are derived from the same source of steam supply. As in the form shown in Fig. 2, the convenient emergency feature is readily obtained by placing the chamber 172 in communication with the pipe 46 leading to the engine cab. Also, ready adjustability of the steam chest

pressure at which the apparatus will effect change in operation of the injector is provided by the simple adjustment of the tension of spring 182 acting on the vent valve 178.

5 From the foregoing description it will be evident that the present invention may be embodied in widely different forms of apparatus and it is therefore to be understood that the invention is in no way limited to the forms of construction 10 shown herein by way of example nor is it to be considered as being limited in its application to the specific forms of injector and control system shown herein. For example, it is evident that the invention is equally applicable to exhaust steam injectors of the multiple-stage type 15 wherein instead of utilizing supplementary high pressure steam in the same stage of the injector as the low pressure steam, the high pressure steam is employed in a separate high pressure or 20 boosting stage. Also, in installations where the injector is intended to deliver only against relatively low pressure and auxiliary live steam alone is sufficient without the aid of supplementary live steam in any form, the present invention is equally 25 applicable.

It is further to be understood that certain features of the invention can be employed to the exclusion of others and the invention is to be considered as embracing all such forms of construction 30 as fall within the scope of the appended claims when construed as broadly as is consistent with the state of the prior art.

What I claim is:

1. In a feed water system including an exhaust 35 steam injector for supplying water to a steam generator which supplies steam to a steam consumer, said injector being of the type adapted to be operated by auxiliary live steam when exhaust steam from said consumer is not available, a control system for changing from exhaust steam to auxiliary live steam operation including a valve for controlling admission of auxiliary live steam to the injector, a connection providing a path for flow of pressure fluid from a source of 40 relatively high pressure to a zone of relatively low pressure, means responsive to variations of pressure in said connection for controlling the position of said valve, valve means for controlling flow through said connection for varying the pressure 45 therein, and means responsive to variations in the pressure of steam supplied to said consumer for operating said valve means.

2. In a feed water system including an exhaust 50 steam injector for supplying water to a steam generator which supplies steam to a steam consumer, said injector being of the type adapted to be operated by auxiliary live steam when exhaust steam from said consumer is not available, in combination therewith, a control system for 55 changing from exhaust to live steam operation including a valve for controlling admission of auxiliary live steam to the injector, a connection providing a path of flow of steam from said generator to a zone of lower pressure, means responsive to variations of pressure in said connection for controlling the position of said valve, valve means for controlling flow through said connection for varying the pressure therein, and means responsive to variations in the pressure of a 60 steam supplied to said consumer for operating said valve means.

3. In a feed water system including an exhaust 65 steam injector for supplying water to a steam generator which supplies steam to a steam consumer, said injector being of the type adapted

to be operated by auxiliary live steam when exhaust steam from said consumer is not available, a control system for changing from exhaust steam to live steam operation including a valve for controlling admission of auxiliary live steam to the injector, a connection providing a path of flow of steam from said generator to a zone of lower pressure, means responsive to decrease of pressure in said connection for opening said valve, valve means for controlling flow through said connection for varying the pressure therein, and means responsive to a decrease to a predetermined value in the pressure of steam supplied to said consumer for opening said valve means.

4. In a control system for an injector adapted to be operated by exhaust steam from a steam consumer and adapted to be operated by auxiliary live steam when exhaust steam from said consumer is not available, a valve for controlling admission of live steam to the injector, means providing a pressure chamber, means for supplying high pressure steam to said chamber, means responsive to pressure variations in said chamber for controlling the position of said valve, means providing a path of flow for freely venting said chamber to a zone of lower pressure, valve means in said path for controlling flow therethrough, and means responsive to variations in the pressure of the steam supplied to said consumer for operating said valve means.

5. In a control system for an injector adapted to be operated by exhaust steam from a steam consumer and adapted to be operated by auxiliary live steam when exhaust steam from said consumer is not available, a valve for controlling admission of auxiliary live steam to the injector, means providing a pressure chamber, means for supplying high pressure steam to said chamber, means responsive to pressure drop in said chamber for opening said valve, means providing a path of flow for freely venting said chamber to a zone of lower pressure, valve means in said path for controlling flow therethrough, and means responsive to a decrease to a predetermined value in the pressure of the steam supplied to said consumer for opening said valve means.

6. In a control system for an injector adapted to be operated by exhaust steam from a steam consumer and adapted to be operated by auxiliary live steam when exhaust steam is not available, a valve for controlling admission of auxiliary live steam to the injector, means providing a pressure chamber, means for supplying high pressure steam to said chamber, means responsive to pressure variations in said chamber for controlling the position of said valve, means providing a path of flow for freely venting said chamber to a zone of lower pressure, valve means in said path for controlling flow therethrough, means providing a second chamber, means responsive to variations in pressure within said second chamber for operating said valve means, and a conduit adapted to contain steam in static condition for communicating to said second chamber pressure variations of the steam supplied to said consumer.

7. In a control system for an injector adapted to be operated by exhaust steam from a steam consumer and adapted to be operated by auxiliary live steam when exhaust steam is not available, a valve for controlling admission of auxiliary live steam to the injector, means providing a pressure chamber, means for supply-

- ing high pressure steam to said chamber, means responsive to pressure drop in said chamber for opening said valve, means providing a path of flow for freely venting said chamber to a zone of lower pressure, valve means in said path for controlling flow therethrough, means providing a second chamber, means responsive to a decrease to a predetermined value of the pressure within said second chamber for opening said valve means, and a conduit adapted to contain steam in static condition for communicating to said second chamber pressure variations of the steam supplied to said consumer.
8. In a control system for an injector adapted to be operated by exhaust steam from a steam consumer and adapted to be operated by auxiliary live steam when exhaust steam from said consumer is not available, a valve for controlling admission of live steam to the injector, means providing a pressure chamber, means for supplying high pressure steam to said chamber, means responsive to pressure variations in said chamber for controlling the position of said valve, means providing a path of flow for freely venting said chamber to a zone of lower pressure, valve means in said path for controlling flow therethrough, means providing a second chamber, means responsive to variations in pressure within said second chamber for operating said valve means, a conduit adapted to contain steam in static condition for communicating to said second chamber pressure variations of the steam supplied to said consumer, and means for operating said valve means independently of the pressure in said second chamber.
9. In a control system for an injector adapted to be operated by exhaust steam from a steam consumer and adapted to be operated by auxiliary live steam when exhaust steam from said consumer is not available, a valve for controlling admission of auxiliary live steam to the injector, means providing a pressure chamber, means for supplying high pressure steam to said chamber, means responsive to pressure drop in said chamber for opening said valve, means providing a path of flow for freely venting said chamber to a zone of lower pressure, valve means in said path for controlling flow therethrough, means providing a second chamber, means responsive to a decrease to a predetermined value in the pressure within said second chamber for opening said valve means, a conduit adapted to contain steam in static condition for communicating to said second chamber pressure variations of the steam supplied to said consumer, and means for opening said valve means independently of the pressure in said second chamber.
10. In a steam locomotive having an operator's cab, a control system for an injector adapted to be operated by exhaust steam from the locomotive engine and adapted to be operated by auxiliary live steam when exhaust steam from the engine is not available comprising a valve for controlling admission of auxiliary live steam to the injector, means providing a pressure chamber, means for supplying high pressure steam to said chamber, means responsive to pressure variations in said chamber for controlling the position of said valve, means providing a path for flow of steam from said chamber to a zone of lower pressure, valve means in said path for controlling flow therethrough, means providing a balance chamber, means for supplying high pressure steam to said balance chamber, means responsive to pressure variations in said balance chamber to a zone of lower pressure, valve means for controlling flow through the vent, means responsive to variations in the pressure of the steam supplied to said balance chamber, means for operating said valve, and independent means for venting said balance chamber to a zone of lower pressure comprising a conduit having an open discharge within said cab and a manually operable valve in said conduit.
11. In a control system for an injector adapted to be operated by exhaust steam from a steam consumer and adapted to be operated by auxiliary live steam when exhaust steam from said consumer is not available, a valve for controlling admission of auxiliary live steam to the injector, means providing a pressure chamber, means for supplying high pressure steam to said chamber, means responsive to pressure variations in said chamber for controlling the position of said valve, means providing a path for flow of steam from said chamber to a zone of lower pressure, valve means in said path for controlling flow therethrough, means providing a balance chamber, means for supplying high pressure steam to said balance chamber, means responsive to pressure variations in said balance chamber for operating said valve means, means for venting said balance chamber to a zone of lower pressure, a valve for controlling flow through the vent, means responsive to variations in the pressure of the steam supplied to said consumer for operating the last-mentioned valve, and independent means for venting said balance chamber to a zone of lower pressure comprising a conduit and a manually operable valve in said conduit.
12. In a control system for an injector adapted to be operated by exhaust steam from an engine and adapted to be operated by auxiliary live steam when exhaust steam from the engine is not available, a first valve for controlling admission of exhaust steam to the injector, pressure responsive means for operating said valve, a second valve for alternatively supplying auxiliary live steam to said injector and to said pressure responsive means, means providing a balance chamber, a piston reciprocably mounted in said chamber and operatively connected to said second valve, means for supplying live steam to both sides of said piston, means providing a path of flow for freely venting said balance chamber to a zone of lower pressure, valve means for controlling flow through said path, and means responsive to variations in the pressure of the steam supplied to said engine for operating said valve means.
13. In exhaust steam injector apparatus, an automatic control system for shifting the injector to live steam operation when exhaust steam is not available including a pressure chamber, means placing said chamber in constant but restricted communication with a source of high pressure steam and means for setting the control system in exhaust steam operating position in response to pressure in said chamber, a vent conduit in communication with said chamber, and a manually controllable valve in said conduit for venting said chamber at will to prevent exhaust steam operation regardless of the presence or absence of exhaust steam.
14. In a locomotive having an operator's cab, exhaust steam injector apparatus including a steam pressure actuated control system for automatically shifting operation of the injector to live steam operation when exhaust steam is not available and vice versa, said system having a pressure

- chamber, means for shifting the system to exhaust steam operating position in response to pressure of steam in said chamber and a conduit for continuously supplying high pressure steam to said chamber when steam is supplied to the engine of the locomotive, a vent conduit communicating with said chamber and having its discharge end located in said cab, and a valve operable from the cab by the operator for controlling flow through said conduit.
15. In a locomotive having an operator's cab, exhaust steam injector apparatus including a steam pressure actuated control system for automatically shifting the injector from exhaust steam operation to live steam operation when exhaust steam is not available and vice versa, said system comprising a vent conduit adapted to be opened to prevent shifting of the system to exhaust steam operating position, said conduit being in communication with a source of steam when the system is in live steam operating position and having its discharge end located in said cab, and a valve operable from the cab by the operator for controlling flow through said conduit.
20. 16. In a steam pressure actuated control system for exhaust steam injectors, means providing a pressure chamber, means for supplying actuating steam to said chamber, an element responsive to pressure in said chamber for shifting the system to exhaust steam operating position, a first conduit for venting said chamber to shift the system from exhaust steam operating position, a valve for automatically closing said conduit under predetermined operating conditions, a second conduit for venting said chamber, and a manually operable valve in said second conduit adapted to be opened to render the automatic closing of the first-mentioned valve ineffective to shift the system to exhaust steam operating position.
25. 17. In exhaust steam injector apparatus, a steam pressure actuated control system for automatically shifting the injector from exhaust steam operation to live steam operation when exhaust steam is not available and vice versa including a pressure chamber in continuous communication with a source of high pressure steam when steam is supplied to the engine from which exhaust steam is derived for injector operation, a vent conduit in continuous communication with
- said chamber and said source for venting said chamber to prevent shift of the injector to exhaust steam operation, and a manually operable valve in said vent conduit.
18. In a locomotive, exhaust steam injector apparatus including a steam pressure actuated control system for automatically shifting the injector from exhaust steam operation to live steam operation when exhaust steam is not available and vice versa, said system including a pressure chamber and means responsive to pressure in said chamber for shifting the injector to exhaust steam operation, conduit means placing said chamber in continuous communication with a source of high pressure steam when steam is admitted to the engine of the locomotive, whereby the injector is normally shifted to exhaust steam operation when steam is admitted to the engine, a vent conduit for continuously venting said chamber of the steam admitted thereto from said source, and a manually operable valve for opening said vent conduit.
19. In a locomotive having an operator's cab, exhaust steam injector apparatus including a steam pressure actuated control system for automatically shifting the injector from exhaust steam operation to live steam operation when exhaust steam is not available and vice versa, said system including a pressure chamber and means responsive to pressure in said chamber for shifting the injector to exhaust steam operation, conduit means for placing said chamber in continuous communication with a source of high pressure steam when steam is admitted to the engine, whereby the injector is normally shifted to exhaust steam operation when steam is admitted to the engine, a vent conduit in continuous communication with said chamber and having an outlet located in said cab and a valve manually operable from said cab for opening said conduit whereby to vent said chamber to cause the injector to be operated as a live steam injector regardless of the presence or absence of exhaust steam and to continuously conduct to the cab high pressure steam from said source when exhaust steam is available and the injector is operated as a live steam injector due to the opening of said vent conduit.

EMANUEL RAWSON.
